LUGGAGE CARRIAGE

Edith F. Alexander, Haverford, Pa.

Application October 9, 1943, Serial No. 505,633

2 Claims. (Cl. 280—61)

This invention relates to carriages useful in transporting suitcases, trunks, or other hand baggage or luggage particularly to and from trains in railway stations.

Due to the heavy increase in passenger traffic and the scarcity of station porters at the present time, most travellers are obliged to tote suitcases and trunks by the handles. This is extremely fatiguing when the luggage is heavy and bulky, especially to women and to elderly persons.

The chief aim of my present invention is to alleviate the conditions resulting from the above mentioned contingencies which desideratum I make possible of realization in practice as hereinafter more fully disclosed, through provision of a carriage in the form of a small skate which will support the weight of a suitcase or trunk and allow the latter to be rolled along; which can be easily and quickly attached to the luggage; and which is small and collapsible into compact form so that it can be readily stored in the suitcase or trunk when its service is not required.

Other objects and attendant advantages will appear from the following detailed description of the accompanying drawing, wherein

Fig. 1 is a top plan view of my improved luggage carriage opened out and ready for application to a suitcase or trunk.

Fig. 2 is a longitudinal sectional view taken as indicated by the angled arrows II—II in Fig. 1.

Fig. 3 shows the edge view of the carriage when collapsed; and,

Fig. 4 is a perspective view showing how the carriage is intended to be used.

From these illustrations it will be noted that my improved luggage carriage includes a pair of flat interhinged wings 5 and 6 fashioned from sheet material preferably of thin plate metal to trapeziform configuration, and, for the sake of lightness, provided with liberal cut-outs 7, 7 and 8, 8 respectively. The abutting edges of the wings 5 and 6 are staggeringly notched as at 9, 9 and 10, 10 with resultant formation of spaced projections 11, 11 and 12, 12 which interfit in aligned relation and which are curled to receive and hold a hinge pintle 13. As shown, in Fig. 1 the pintle 13 extends beyond the opposite side edges of the wings 5 and 6 for the journaling of rollers 14 and 15 which constitute the floor or pavement contacting means of the carriage, the ends of said pintle being headed over as at 16 and 17 to retain said rollers. The carriage further includes an extensible strap formed by two sections 18 and 19 which are adjustably con-

nected by a buckle 20, see Fig. 4. At one of its ends the strap section 19 is provided with a buckle 21 to receive the free end of the strap section 18. As shown in Figs. 1 and 2, the strap is passed through contiguously disposed transverse slots 22 and 23 adjacent the swinging edges of the wings 5 and 6 centrally of the latter and so held assembled with the carriage.

In preparation for use the carriage is attached 10 to a suitcase or trunk in the manner shown in Fig. 4, that is to say, placed so that its wings 5 and 6 lap adjacent sides of the suitcase or trunk at one corner of the latter, whereupon the strap is applied perimetricaly about the trunk and the free end of its section 18 connected by the buckle 21 at the free end of the section 19. In order to facilitate control of the suitcase as it is rolled along on the carriage, the strap section 19 is provided with a plurality of grasp loops 25, 26 and 27 which may be selectively used to suit the convenience of the user.

From Fig. 4 it will be further noted that the carriage is small as compared to the suitcase or trunk, and due to the interpivoting of its wings 5 and 6 can be collapsed into compact flat form as shown in Fig. 3 and its strap wrapped thereabout. Accordingly, when its use is not required the carriage can be readily stored within the suitcase or trunk without taking up an objectionable amount of space.

Having thus described my invention, I claim:

1. A collapsible luggage carrier comprising complementary flat wings having the meeting edges staggeringly notched and curled to define aligned hinge junctures, a pintle fitted through said junctures with extension at both ends therebeyond, a roller journaled on each such pintle extension with means retaining the same against axial displacement, and a flexible strap passed through apertures in the flat wings and medially outwards over the hinge junctures for securing the luggage carrier to the corner edge of a suitcase or the like whereby said suitcase or the like can be easily moved about.

2. The invention as defined in claim 1 wherein the respective flat wings are of plate metal and trapeziform in configuration with liberal cut-outs for the sake of lightness, the aligned hinge junctures are formed along the major of the 50 paralleling sides of said flat wings, the strap apertures are in the form of transverse slots adjacent the swinging edges of the respective wings, and the means for retaining the rollers against displacement consists in heading over the ends of the pintle.

EDITH F. ALEXANDER.
